UNITED STATES PATENT OFFICE.

CONSTANTIN CARL KLINIK, FRIEDRICH PINKOWSKI, AND AUGUST GROSS,
OF KÖNIGSHÜTTE, PRUSSIA, GERMANY.

HYDRAULIC PUNCHING-MACHINE.

SPECIFICATION forming part of Letters Patent No. 404,633, dated June 4, 1889.

Application filed November 7, 1887. Serial No. 254,729. (No model.) Patented in Germany February 12, 1887, No. 41,746.

To all whom it may concern:

Be it known that we, CONSTANTIN CARL KLINIK, FRIEDRICH PINKOWSKI, and AUGUST GROSS, of Königshütte, in the Kingdom of Prussia and German Empire, have invented new and useful Improvements in Hydraulic Punching-Machines, of which the following is a specification, reference being had therein to the accompanying drawings, no 10 patents being obtained by us anywhere for this invention except in Germany, February 12, 1887, No. 41,746.

Our invention relates to hydraulic motors and the application of the same to mechanical 15 devices; and it consists in an improved construction of hydraulic motor and press applied to a punching-machine, as hereinafter described and claimed.

In the accompanying drawings, Figure 1 20 represents a vertical section of our device, showing the operating mechanism. Fig. 2 is an elevation, certain parts of the device being shown in section. Fig. 3 is a horizontal section taken on line *a b* of Fig. 1. Fig. 4 is a 25 like section on line *c d* of Fig. 1. Fig. 5 is a detached view of a plate which forms a housing for connecting gear-wheels. Fig. 6 is a section taken on line *e f* of Fig. 1.

In the drawings, *A* designates the liquid- 30 reservoir, the base *C* of which is screwed on the cylinder *B*, within which is placed a pressing-piston *K*. The reservoir and cylinder are further secured by bolts *a'* and securing-nuts, as shown. The threaded surface of the cylinder *B* is formed on a ring, which is driven 35 in place on the cylinder in a heated condition, and thus firmly secured. The base *C* is provided with threaded holes *F* for the attachment of handles to be used in attaching it to 40 or removing it from the cylinder *B*.

Within the reservoir *A* are placed two pumps *P' P²*, the lower extremities of the pump-cylinders being screwed into perforations through the base of the reservoir, as 45 shown. The pump-cylinders are provided with lateral valves *P*, through which liquid is drawn into the cylinders during operation.

The rods *d* of the pump-pistons are connected, as shown, with a crank-shaft *W*, having 50 bearings in the upper part at the joint

between the reservoir-casing and the removable top or cover *D*, so that as the crank-shaft is rotated the pistons of the pumps are moved up and down alternately. The cover *D* is secured by bolts and nuts to the casing of the reservoir, and a close joint is formed between these parts. A tubular passage *i* in the cover is for the purpose of supplying the reservoir with liquid, and is closed by means of a screw *l* and a leather washer. 55

The crank-shaft *W* is extended at one end, a stuffing-box *t* being provided at its bearing, and a gear-wheel *h* is placed on the shaft, said wheel engaging with a smaller gear-wheel *r*. The wheel *r* is on a shaft *m*, being 60 made solid therewith, and has bearings in the casing of *A* and in a removable plate *E*, which forms a housing for the wheels *h* and *r*. A crank *F'* may be applied to either of the shafts *W m*, according to the speed of rotation of the crank-shaft required. The piston *K*, being provided with packing, fits in the cylinder *B* and forms a pressure-head for the stock *n* of the cutting-tool *o*, extending 65 downward, as shown. A small passage *s* forms communication between the reservoir and the cylinder *B*, said passage being opened or closed by means of a screw-valve *v*, which is provided with a handle *q*. The passage *s* is kept closed during operation, and is opened 70 to remove the pressure of liquid from the head *K* in the cylinder. 75

A spiral spring *S* is placed under the head *K* in the cylinder for the purpose of raising the head when it is released from the pressure of the liquid. 80

The pumps being operated by the rotation of the crank-shaft, liquid in the reservoir is drawn through valves *P* into the pump-cylinders and is pressed down into cylinder *B* 85 against the head *K*, which is forced downward, thus actuating the cutting-tool. When the work is completed, the valve *v* is opened, allowing the passage of liquid from cylinder *B* to the reservoir, and the head *K*, being released, is immediately raised by the spring *S*. 90

We claim—

The combination of the reservoir *A*, the cylinder secured to the base thereof and having the pressure-piston, the pumps arranged with- 100

in the reservoir and having their lower ends screwed to the base thereof, the cap D, secured to the upper end of the reservoir, said cap and reservoir having the bearings formed in 5 their meeting ends, the plate t, secured to the cap and reservoir, the housing E, bolted to the cap and reservoir, the crank-shaft journaled in the bearings in the reservoir and cap and in openings in the plate t and housing E, 10 the cranks of the said shaft being connected to the pump-plungers, the wheel h on the said shaft, the shaft m, journaled in bearings in the housing and in the reservoir, and having

the pinion r, meshing with wheel h, and the crank F', adapted to fit on the outer ends of 15 either the crank-shaft or shaft m, substantially as described.

In witness whereof we have hereunto set our hands in presence of two witnesses.

CONSTANTIN CARL KLINIK.
FRIEDRICH PINKOWSKI.
AUGUST GROSS.
